ARTICLE FEED FOR WRAPPING MACHINES

Filed Oct. 29, 1929

FIG. 1

FIG. 3

FIG. 2

INVENTOR
Charles Kehling
BY
Sydney D. Prescott
ATTORNEY

UNITED STATES PATENT OFFICE

CHARLES KEHLING, OF BROOKLYN, NEW YORK, ASSIGNOR TO AMERICAN MACHINE & FOUNDRY COMPANY, A CORPORATION OF NEW JERSEY

ARTICLE FEED FOR WRAPPING MACHINES

Application filed October 29, 1929. Serial No. 403,237.

This invention relates to article feeds for wrapping machines, and particularly to that type in which the articles are fed in a row down an inclined chute, at the bottom of which they are withdrawn by a transverse conveyor by which they are moved into the machine in a direction at right angles to the length of the row on the chute.

In the case of articles of somewhat irregular or variable shape or rough surface texture, such as loaves of bread, particularly when the latter are sliced before being fed into the machine, the surface disturbance between the upper side of the article on the conveyor and the lower side of the last article on the feed chute has been found sufficient to cause considerable trouble through disarrangement or injury of the article being withdrawn on the conveyor or the adjacent article in the chute; or in the case of sliced loaves, through skewing of the slices.

It is the object of the present invention to so arrange the article feed as to reduce this disturbance to a minimum. To this end, there is interposed in the path of the descending article, just as it enters into the delivery position upon the conveyor, a hump so placed that it raises the forward end of the last article on the chute and the rear end of the article on the conveyor, thereby separating the articles, so that they touch along a single line of contact, thereby reducing surface friction between them.

With this and other objects not specifically mentioned in view, the invention consists in certain constructions and combinations which will be hereinafter fully described, and then more particularly pointed out in the hereunto appended claims.

In the accompanying drawings in which like characters of reference indicate the same or like parts:

Fig. 1 is a side elevation of an article feed constructed in accordance with the invention;

Fig. 2 is a plan view of the device shown in Fig. 1; and

Fig. 3 is a side elevation of the article feed with the article separating hump detached.

In carrying the invention into effect, there is provided in combination with a runway

for supplying articles in side by side row formation, a conveyor arranged to withdraw articles transversely from said row, together with means for relatively tilting the article next to be withdrawn and the adjacent article in the row to reduce the friction between their sides, thus avoiding accidental shifting of position or injuring of said articles. In the best constructions, said means will comprise a device providing a hump on the loaf supporting surface of the runway. The various means referred to may be widely varied in construction within the scope of the claims, for the particular construction selected to illustrate the invention is but one of many possible concrete embodiments of the same. The invention, therefore, is not to be restricted to the precise details of the structure shown and described.

Referring now to the drawings, a runway, preferably a chute such as the chute 5 is shown for supplying articles in side by side row formation. This runway is supported by bars 6 attached to lugs 7 carried by shafts 8 fastened to the frame of the wrapping machine. The chute 5 has at either side adjustable guides 9 which are attached to rods 10 carried by studs 11 slidably in the lugs 7 and held in position by thumb-screws 12.

At its lower end, the chute 5 leads onto a plate 13 supported on bars 14, this plate, together with a second plate 15, spaced a short distance from it on bar 16, forming the runway of the article conveyor which in the form illustrated is the feed conveyor of a bread wrapping machine, which conveyor is provided with an adjustable end wall 17 carried by posts 18. The space between plates 13 and 15 forms a slot through which enter pushers 19 attached to a conveyor chain 20 driven by a sprocket 21. The portion of the conveyor runway adjacent the lower end of the chute 5 also forms a continuation of the article supporting surface of the chute and a part of the article supplying runway.

Upon the plate 13 is mounted the hump forming device 22 which is of wedge shaped outline and so dimensioned that the space between its flat end and the end wall 17 of the conveyor is smaller than the width of the

article P to be wrapped. The device 22b shown in Fig. 1 is preferably formed of sheet metal and has along its trailing end, corresponding to the edge of the wedge, a hooked edge designed to hook detachably into the slot between the chute 5 and the plate 13, so that the straight body portion 22b forms a continuation of the article supporting surface of the chute, of reduced slope. This portion of the hump of reduced slope is followed by an abrupt drop formed by the supporting wall 22a, off which the loaves or other articles tilt, as shown at P' in Fig. 1. It will be noted that for this purpose the high spot of the hump is between the centers of gravity of the end article or article next to be withdrawn and the article adjacent thereto. Thus the article arrives in the range of action of the conveyor in the tilted position P' in which it has contact with the adjacent article P on the incline along a single line only. The article forwarded on the conveyor remains in the position P' until after it has passed the article P on the chute, and after being clear of the incline 22b, assumes the position P'' on the runway of the conveyor.

Without the hump forming device 22, the article P, as shown in Fig. 3, is delivered by the chute to the conveyor runway in the position P'', so that the entire upper side of the article P'' is in contact with the lower side of the last article P on the chute. The improved feed chute by which the contacting surface and resulting friction is greatly reduced, thus eliminates a source of trouble heretofore encountered with article feeds of this type.

What is claimed is:

- 40 1. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles.
- 50 2. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles, said means comprising a device for lifting one side of one of said next and adjacent articles.
- 60 3. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles, said means

comprising a device providing a hump on the loaf supporting surface of said runway.

4. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles, said means comprising a device providing a hump on the loaf supporting surface of said runway, and a hook structure at the trailing edge of said device for detachably securing said device on said runway.

5. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles, said means comprising a device providing a hump on the loaf supporting surface of said runway, the highest point of elevation of said hump with respect to the general level of the runway being between the centers of gravity of said next and adjacent loaves.

6. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles, said runway comprising a chute, and said means consisting of a device providing a continuation of the surface of said chute of reduced slope followed by an abrupt drop.

7. In an article feed, the combination with a runway for supplying articles in contacting row formation, of a conveyor arranged to successively withdraw articles transversely from said row, and means for relatively tilting the article next to be withdrawn and the adjacent article in the row to reduce the friction between said articles, said means consisting of a device of wedge shaped outline secured in said runway with the wedge edge trailing.

8. An article tipper for tipping articles in a runway to reduce their surface of contact without impeding their forward progress along the runway, comprising a device of wedge shaped outline with a hooked edge for detachably securing said device to the runway.

In testimony whereof, I have signed my name to this specification.

CHARLES KEHLING.
